UNITED STATES PATENT OFFICE.

WILLIAM WHITE, OF WHITE PLAINS, NEW YORK.

STREET-RAILWAY SWITCH.

SPECIFICATION forming part of Letters Patent No. 396,128, dated January 15, 1889.

Application filed October 29, 1887. Serial No. 253,701. (No model.)

To all whom it may concern:

Be it known that I, WILLIAM WHITE, of White Plains, in the county of Westchester and State of New York, have invented a new 5 and useful Improvement in Street-Railway Switches, which invention is fully set forth and illustrated in the following specification and accompanying drawings.

The object of this invention is to furnish a 10 simple and practicable mechanism for that class of switches in which a tilting or vibrating platform is operated by the horse or horses drawing the car to effect the necessary movement of the vibrating tongue of the switch, 15 which mechanism shall be easily accessible within a much shallower pit than commonly used for said class of switches, while the necessary motion given to the tilting platform and the number of wearing-points shall also 20 be greatly diminished or reduced to a minimum.

The invention consists of the parts and combinations of parts, as hereinafter described and claimed.

25 In the accompanying drawings, Figure 1 is a top plan of the switch. Fig. 2 is a bottom plan of the same. Fig. 3 is a vertical cross-section taken at the line *x x* of Figs. 1 and 2. Fig. 4 is a similar section taken at the line *y y* of Figs. 1 and 2. Fig. 5 is a similar section, enlarged, taken at the line *z z* of Figs. 1 and 2. Figs. 6 and 7 illustrate details hereinafter described.

The letter A indicates the tilting platform; 35 B, a fixed plate or cover forming part of the space between the rails; C, the switch-plate and rails; and D, the movable tongue of the switch pivoted at *d* and at *c* articulated to a connecting-rod, E, provided with a turn-buckle, F, the opposite end of said rod being riveted or bolted, as at *b b*, or otherwise secured, to a flat spring, e, bent over and secured by bolts or rivets *f* to one arm of a bell-crank, G, secured by a stud or screw-bolt, g, 40 to a chipping piece or block, H, on the end of the frame R. The other arm, *k*, of said bell-crank G terminates in a double beveled point, which is entered into a correspondingly-recessed follower, K, bearing against a coiled 45 spring, J, said follower and spring being each contained within a recess, M, formed in the head of the arm L, whose opposite end is se-

cured fast on the rock-shaft I by a set-screw, *h*, or otherwise. Said shaft is journaled in bearings *m m*, secured to transverse frame Q 55 and end frame, R. On said shaft I is secured fast a double-armed lever or beam, N, Fig. 3, each arm of which rises to close contact, as at *n n*, with a cross rib or web, O, secured fast to the tilting platform A, pivoted at each end 60 in bearings *a a* on the end frame, P, and transverse frame S, Fig. 2. Either arm of the yoke or beam N may be counterweighted to balance any tendency in the weight of the operative parts to throw the yoke, and with it 65 the table A and tongue D, to the wrong side.

The operation of all the said parts can now be easily understood, and is as follows: When the weight of the horse is brought upon the tilting platform A to either one side or the other, as the driver may determine, the platform is depressed to one side on its pivotal points *a a*. This movement of the platform is transmitted to the movable tongue and throws its point full over to one side or the other, so that the car following the horse and entering upon the switch is either deflected by the point of the tongue D to the curved track or else runs past said point and continues along on the straight track. The tongue 75 D receives said movements from the tilting platform A by the following instrumentalities: The cross rib or web O, in contact with the arms of the double-ended lever or beam N, transmits to either arm of said beam the 80 weight of the horse on the platform A. Said beam then oscillates the rock-shaft I, which in turn rocks the arm L, containing within the socket M, in its head, the spring J and follower K, which arrangement makes a flexible junction between said follower and the end of one arm, *k*, of the bell-crank G. Said bell-crank will thus be actuated by the oscillation of the arm L, and through its other arm, *j*, said bell-crank will, through the interposed 85 spring connection or arm *e*, actuate the spring connecting-rod E, and through its intervention transmit the necessary movements to operate the tongue D, to which said connecting-rod E is articulated, as at *c*, sufficiently remote from the pivotal point *d* of said tongue to afford the necessary leverage for operating it. The tongue D may be secured at its pivotal point by any suitable pin or fastening, or 90 95 100

by pin, key, and collar, in the manner shown and claimed in another application herewith filed by me, numbered 253,700, of even date herewith, but to which I herein make no claim.

5 The connecting-rod E may also be secured to the tongue at the point c, as shown and claimed in my said application, (but herein not claimed,) by a countersunk screw-threaded nut on the end of the rod bent up and inserted 10 in a square hole in the tongue below said countersunk nut; or any other suitable mode of attachment may be adopted.

In Fig. 7 is shown in three views, detached, one of the stops s, which are shown in Figs. 2 15 and 4. Said stops limit the throw or arc of oscillation of the table A, which arc is very small, the spring-connections between the arm L and connecting-rod E and the turn-buckle F on the latter serving to regulate any wear 20 that may take place, so that the tongue D will always be quickly thrown completely over when the table is tilted through its small arc of vibration. The stops s are provided 25 with grooves r, which are inclined, as indicated at x in the several views of Fig. 7. These grooves lead from the surfaces of the internal fastenings of the box-frame of the switch, and thus conduct any water rapidly away that may fall upon and between the table A and adjacent parts.

The yoke or beam N and the cross-web O may have their contact - surfaces either straight or flat, as shown, or slightly curved. The less their arcs of vibration, however, the 35 less need, it is obvious, there will be for any curvature of surfaces between them. It will be observed that the tilting table A is not only braced by the cross - web O, through which it communicates its tilting motion to 40 the tongue D, but said web has formed as part thereof another and longitudinal web, w, under the middle of the table and running its entire length to its pivotal points a a. The table is thus thoroughly braced both longitudinally and transversely. It is also located entirely within the rails, thus exempting 45 it from much destructive wear of and operation by ordinary vehicles and wagons passing outside of the track. Only the ears 50 and those vehicles passing inside the rails can operate this table, and consequently the tongue D, which tongue in any event is immediately restored to its normal position, whenever moved, as soon as the moving body 55 passes, whether the tongue be moved by the depression of the table or by the flanges of

car - wheels approaching the point of the tongue from the direction of its heel or not.

The construction of the whole plant or frame of this switch is such that only a very 60 shallow pit is required, and only a small plate or cover, T, is requisite to enter that portion of the pit where the main operative parts are situated. The extreme points, marked W and V, Figs. 1 and 2, of the switch-plates or 65 rails C may be secured to the track-rails in any suitable and well-known manner.

Having thus fully described said improvement in street-railroad switches as of my invention, I claim—

1. In combination with a tilting platform, as A, a rock - shaft, as I, provided with a double-armed lever or beam, as N, and an arm, as L, having within a socket therein a spring, as J, and a follower, as K, a bell-crank, as G, a 75 bar-spring, as e, and a connecting-rod, as E, united to said crank by said spring and articulated to a vibrating tongue, as D, whereby said tongue is operated by the tilting of said platform, substantially as and for the purposes set forth.

2. In a movable-tongue switch, a bell-crank, as G, having one arm adapted to receive a spring, as e, and another arm adapted to receive the reaction of another spring, substantially 85 as and for the purposes set forth.

3. In a movable-tongue switch, a spring, as J, socketed within a vibrating arm, in combination with a follower, as K, substantially as and for the purposes set forth.

4. In a street-car switch, in combination with a movable tongue, a spring connecting-rod secured thereto for operating the same, substantially as and for the purposes set forth.

5. In a movable-tongue switch, a tilting platform or table provided with transverse and longitudinal braces, as O w, substantially as and for the purposes set forth.

6. In a movable-tongue switch, a stop or stops, as s, secured to the framing of the switch to limit the arc of vibration of the tilting platform, and provided with inclined grooves or gutters for rapidly conducting away any water falling upon and between said platform and adjacent parts of the switch 100 box or framing, substantially as and for the purposes set forth.

WILLIAM WHITE.
